Primary Examiner — George D Kirschbaum*Assistant Examiner* — Kendra L Hamilton(74) *Attorney, Agent, or Firm* — Stacy H. Combs; Thomas C. Feix(57) **CLAIM**

The ornamental design for a sleeve for a water pitcher, as shown and described.

DESCRIPTION

FIG. 1 is a front perspective view of the sleeve of the present invention;

FIG. 2 is a top view thereof;

FIG. 3 is a bottom view thereof;

FIG. 4 is a left side view thereof, the right side being a mirror image;

FIG. 5 is a front side view thereof; and,

FIG. 6 is a back side view thereof.

The broken line showing of environmental structure is included for the purpose of illustrating portions of the "article" and forms no part of the claimed design.
